THERMAL CIRCUIT INTERRUPTER

Elmer H. Taylor, Newburyport, Mass., assignor to
 The Chase-Shawmut Company, Newburyport,
 Mass., a corporation of Massachusetts

Application June 9, 1938, Serial No. 212,735

15 Claims. (Cl. 200—123)

This invention relates to fusible protective devices employing a conducting structure having separable parts maintained in circuit closed connection by a readily-fusible low melting temperature material which is adapted to be melted to permit the separation of the parts and the interruption of the circuit.

In a device of this type it is common to provide an electric resistance element to heat the fusible mass and a fuse link to provide for the instant interruption of the circuit upon a severe overload approaching a short-circuit.

It is one of the objects of the present invention to simplify the construction of such a protective device and at the same time to improve the operation thereof by utilizing the heat generated in the fuse link to melt the fusible mass and effect interruption of the circuit upon long continued small overloads, thereby eliminating the heating resistor.

It is also an object of the present invention to control the time required for the readily fusible material to melt when the device is traversed by an overload current that is not sufficient to fuse the fuse link by the use of a fuse link one end of which is normally anchored by the fusible material, the link having such mass, preferably concentrated near the fusible material, that the elevation in temperature of that end of the link that is anchored by the fusible material to the melting point of the material is delayed for the desired period of time.

Another object of the invention is the provision of a device of the general type above set forth wherein the dissipation of heat by conduction from the fusible material externally of the device is controlled.

A yet further object is generally to improve the construction and operation of fusible protective devices.

The device of the present invention in one of its aspects comprises an enclosing body of the plug fuse type having a terminal and a center contact wherein the fusible material is located in the center contact and the fuse link is connected releasably to the center contact by the fusible material and is also connected to the terminal. In this respect this application is a continuation in part of the copending application of Morris B. Wood, assigned to the assignee of this application, Serial No. 32,385, filed July 20, 1935, on which Letters Patent No. 2,168,815 were granted August 8, 1939.

Fig. 1 is a plan view of a fusible protective device of the plug fuse type embodying the present invention.

Fig. 2 is a sectional elevation taken along line 2—2 of Fig. 1 with the parts in circuit closed position, the device being illustrated as positioned within a receptacle.

Fig. 3 is a section similar to Fig. 2 of the device per se but with the parts in circuit open position in response to the fusing of the fusible mass.

Fig. 4 is a plan view of the structure of Fig. 3 illustrating the position of the movable parts in circuit open condition.

Fig. 5 is a sectional elevation of the device similar to Fig. 2 but with the parts in open circuit position resulting from the fusing of the fusible link.

Fig. 6 is a view similar to Fig. 2 but illustrating a modified form of device of the so-called non-tamperable type and having a modified arrangement of its current responsive parts.

Fig. 7 is a plan view of the fuse link of Fig. 2.

Fig. 8 is a longitudinal section of a modified form of the device in a cartridge type of enclosing casing.

Fig. 9 is a view similar to Fig. 8 but showing a further modified form of device.

Figs. 1 through 6 illustrate the invention as applied to a device of the plug fuse type. The device includes a cylindrical insulating enclosing casing 12 of porcelain, for instance, having the bottom wall 14 at one end, the radially outstanding flange 16 at the other end, and a chamber 18 open at the flange end of the body and closed by the integral bottom wall 14. The open end of the chamber is closed by a transparent closure disc 20, as mica, for instance, held in place by an overlying metal cap 22 having a window 24 therein which confronts the chamber 18. The cap has a rim 26 which encircles the flange 16 and the lower edge part 28 of the rim is inturned under the flange. The body 12 is provided with a terminal in the form of an externally screw-threaded metal shell 30 which is located on the cylindrical portion of the body. A center contact 32, formed as a tubular rivet, extends through the

middle portion of the end wall 14 and is fixed in place. The center contact has a recess or well 34 in its inner end accessible to the chamber 18. A body or mass 36 of readily fusible metal is located within the recess 34. The solid body 36 of

the contact between the bottom of the well and the contact face 35' is sufficiently long to prevent harmful dissipation of heat by conduction from the fusible mass to the terminal of the receptacle.

A fusible link 38 is located within the chamber 18 and has one end thereof connected to the center contact by being imbedded in or attached to the normally solid readily fusible metal 36. The link extends upwardly within the chamber and thence approximately horizontally to the top of

a passage 40 in the side wall of the body 12 and thence downwardly to the bottom of the passage where it is connected through a mass of solder 42, or otherwise, with the screw shell 30.

Spring means are associated with the link to withdraw it from the readily fusible mass when

said mass melts and releases its hold on the link. Said spring means includes a spring wire 44 having one end 48 depending downwardly and seated removably in a vertical recess in a shoulder 46 of the plug body. The spring has a portion 50 extended at right angles to the end part 48 and generally parallel with the approximately horizontal part of the link and at one side thereof which in the middle part of the casing has a downwardly depending part 52 that has a horizontal lower part 54 that is located under the link and exerts an upward tension thereon. The link preferably is provided with a transverse loop 56 in which the spring end 54 is located. The portion 52 of the spring wire is swung from the substantially horizontal position shown in Fig. 3 to the position shown in Fig. 2 which places the spring wire under tension when the fuse is being assembled. The portion 54 of the spring wire acts as a hook and prevents any appreciable rotation of the wire about the portion 48. Between the spring and the center contact and preferably near but under the spring the link has a reduced cross-sectional area provided conveniently by the perforation 58 which is located in the middle part of the link and determines the fusing point of the link upon short-circuit. The cross sectional area of the link at the perforation determines the overload blowing current and also is a source of heat generation.

The nature of the material of the link and the dimensions thereof depend upon the characteristics of the circuit to be protected. The link may comprise a flexible copper strip or ribbon which has been found to be highly satisfactory. For some purposes, however, the link can be composed of a flexible strip of material having greater electrical resistance than copper and thereby greater heat generating property such, for instance, as a strip of copper-nickel alloy of suitable dimensions. The strip 38 of whatever material it is composed constitutes both the fusible link which protects the circuit against short-circuit currents and the heater for the fusible mass 36. The readily fusible metal 36 is an alloy, or a single metal, having a melting temperature preferably lower than the melting temperature of the link.

A fuse link necessarily generates heat when traversed by an electric current and the heating of the link is herein utilized to melt the fusible mass 36. It is apparent that heat will be transmitted from the link to the fusible mass and when the temperature of the fusible mass becomes sufficiently high it will melt and release its grip on the end of the link, thereby permitting the spring to pull the link out of the fusible mass into some position as illustrated in Fig. 3, and thereby interrupt the circuit. In the circuit open position the link is in substantial contact with the transparent disc 20 or at least the released parts are closer thereto than before operation so that the open circuit condition of the device can be discerned readily. The metal mass 36 is intended to fuse about the link and interrupt the circuit when the device is traversed for a substantial period of time by an overload current which, however, is not great enough to cause the fusing of the fuse link. The device is so arranged, however, that the metal mass will not melt within the time required for the link to fuse at the most readily fusible portion 58 when the device is traversed by high overloads approaching a short-circuit. Hence under such conditions the link will fuse instantly at the perforation and

the spring is effective in widening the circuit interrupting gap as illustrated in Fig. 5.

The desired delay in heating the fusible mass to the melting temperature when the device is traversed by moderate overload is herein obtained by a heat absorbing member 60 attached to the fuse link preferably between the short-circuit perforation 58 and the fusible mass 36. The heat absorbing member as here shown comprises a cylindrical button having a projection 62 on one end face which is extended through a perforation of the link and is headed over thereupon so that the end face of the button is in good thermal contact with the link. The button preferably is of a material as copper that has high thermal conductivity and specific heat and the amount of material of the button is selected to obtain the desired time lag of melting of the fusible mass 36. It is apparent that the temperature of that end of the link imbedded in the fusible mass 36 cannot rise in temperature any faster than is permitted by the absorption of heat by the button and hence the heat absorbing property of the button largely control the time delay of melting of the mass 36. Preferably the button 60 is relatively close to the fusible mass so that the length of link intervening between the metal mass and the button does not generate much heat.

The fuse link at the end part passing within the channel 46 and soldered to the screw shell 18 is preferably enlarged as at 64, Fig. 7, so that the heating portion of the link is the narrow part of the link and the reduced area part at the perforation 58 and variable amounts of solder 42 do not seriously influence the operating characteristics of the device.

In the modification illustrated in Fig. 6 the device is of the non-tamperable type. In this modification the insulating plug body 12a has a hexagonal recess 66 in the end face of the end wall 14a thereof in which the hexagonal end wall 68 of a cylindrical tubular tamper preventing member 70 is received so that relative motion between the tamper preventing member and the plug body is prevented. The bottom end of the tamper preventing member is provided with teeth 12 and interposed indentations. The tamper preventing member is adapted to cooperate with a complementary member, not here shown, located in the fuse receptacle for dislodging any foreign terminal bridging conducting matter that may be inserted therein. The center contact of this modification of device comprises a long tubular member 74 the lower end 76 of which is located below the tamper-preventing member 70 and is adapted to make contact with the center contact of the receptacle receiving the device. The tubular contact is provided with outstanding flanges 78 and 80 which secure the contact member to the plug body and anchor the tamper preventing member 70 thereto. The wall of the contact member is intended to be sufficiently thin if made of good heat conducting material, or is sufficiently long to provide a suitable thermal drop between the top and bottom ends thereof. A mass of readily fusible material 81 corresponding to the fusible mass 36 is located in the upper end of the tubular contact. In this modification the fuse link 38a having the most readily fusible portion 58a and stressed by the spring 44 has its end affixed, as riveted, to one end of the heat absorbing button 60a. The other end of said button is electrically connected to the center contact member by the fusible mass 81 which can be in direct contact with the lower end face or with a smaller projec-

tion 68b thereof. In this modification the heat of the fuse link traverses the heat absorbing button and ultimately heats the fusible mass sufficiently to cause the mass to lose its hold on the button whereupon the spring 44 moves the button and the fuse link away from the mass, thereby opening the circuit. The rate of temperature rise is reduced by the heat absorbing capacity of the button.

Figs. 8 and 9 are longitudinal cross sections of a cartridge type of device employing the present invention, Fig. 8 representing a construction adapted for currents say up to 15 amperes, and Fig. 9 representing a construction adapted for higher currents. The devices of both of these figures include a tubular insulating casing 82 having end caps 84 and 86 thereon. A fusible link 88 is extended through the casing and connected to the end wall of the end cap 86 by a suitable means, as solder 90, having a melting point sufficiently high so that the solder is not adapted to melt during operation of the device. The other end of the link is connected to the end wall of the other end cap 84 by a mass 92 corresponding to the mass 36 of Figs. 2, 3 and 5, of readily fusible or low melting temperature solder. The link is provided with a perforation 94 or other equivalent means for forming a reduced cross section of the link to provide a more readily fusible portion on short-circuit current. The reduced cross sectional area of the link at the perforation is also a source of heat as is the case with the perforation 58 of the previous modifications. The heat absorbing block 96 of copper or other good heat absorbing material is secured to that portion 88a of the link between the perforation 94 and the fusible mass 92 and in good heat conductivity with the link to secure the desired delay of fusing of the fusible solder 92, or that portion thereof in direct contact with the link. A tension spring 98 has one end connected to the link as by being connected to the heat absorbing block 96 to pull the end of the link from the fusible mass when the latter releases its hold on the link. The other end of the spring is provided with a hook 100 which is hooked over the end of the enclosing casing under the end cap 86 or is otherwise anchored.

Essentially the same arrangement is embodied in the construction illustrated in Fig. 9. In this modification the enclosing casing is provided with two compartments formed by an internal ledge 102 of the enclosing casing and an insulating disc or washer 104 which is seated upon the ledge. The tension spring in this instance is anchored to the disc and holds it seated upon the ledge. The fuse link extends through the disc and in the left end chamber 106 is provided with a locality of reduced cross-sectional area as by the perforation 108 where the fuse is adapted to blow upon short-circuit. The chamber 106 can contain an arc suppressing medium 110. The perforation 108 can be larger than the perforation 94 so that the fuse link will be ruptured on short-circuit current at the perforation 108 and within the chamber 106.

I claim:

1. A thermal circuit interrupter including terminals, a fusible link having a most readily fusible portion extended between and electrically connecting said terminals, a readily fusible metal connecting said fuse link electrically to one of said terminals, said most readily fusible portion of said link being adapted to become heated by the current traversing it and to heat and soften

said fusible metal, means responsive to the softening of said fusible metal to effect separation of said fuse link and said one terminal, and means to delay the fusing of said fusible metal including a heat absorbent mass supported by and in thermal relation with said fuse link between said most readily fusible portion and said fusible metal.

2. A thermal circuit interrupter including external terminals, a conductor extended between and electrically connecting said terminals, a mass of heat absorbent material thermally connected to said conductor, a mass of readily fusible material electrically and mechanically connecting said conductor and said mass of heat absorbent material to one terminal, said conductor being adapted to become heated by the current traversing it and to heat said fusible material and to cause said material to loosen its hold on the conductor, and spring means acting on said conductor and responsive to the fusing of said fusible material to move the conductor and said mass of heat absorbent material away from the fused fusible material.

3. A thermal circuit interrupter including external terminals, a conductor extended between and electrically connecting said terminals, a mass of heat absorbent material thermally connected to said conductor, a mass of readily fusible metal electrically and mechanically connecting said conductor and heat absorbent mass to one terminal, said conductor being adapted to become heated by the current traversing it and to heat said fusible metal and to cause said metal to loosen its hold on the conductor, and spring means operative to effect separation of the conductor and heat absorbent mass from the heated fusible metal, said conductor comprising a fusible link supporting said mass of heat absorbent material having a part adapted to fuse to interrupt the circuit in a shorter period of time than is required for the fusible metal to release its hold on the conductor when the conductor is traversed by a sufficiently heavy current.

4. A thermal circuit interrupting device of the plug type comprising a casing having means providing screw threads and a terminal and a center contact, a conductor extended between and electrically connecting said terminal and center contact and being connected with a stationary part of said center contact by a readily fusible mass that is in thermal association with the conductor, said conductor adapted to be heated by sufficient current traversing it for a sufficient period of time to effect the heating of said fusible metal to cause it to release its hold upon said conductor, a heat absorbent mass thermally connected to said conductor, and spring means operative upon sufficient weakening of the hold between said fusible metal and conductor to effect separation of the conductor and the heat absorbent mass from the center contact.

5. A thermal circuit interrupting device comprising a casing having a terminal and a center contact, a conductor extended between and electrically connecting said terminal and center contact and being connected with said center contact by a readily fusible mass that is in thermal association with the conductor and is attached to a stationary part of said center contact, said conductor adapted to be heated by sufficient current traversing it for a sufficient period of time to effect the heating of said fusible mass to cause it to release its hold upon said conductor, a heat absorbent mass thermally connected to said con-

ductor, and spring means operative upon sufficient weakening of the hold between said fusible mass and conductor to effect separation of the conductor and heat absorbent mass from the center contact, said conductor comprising a fusible link having a portion adapted to fuse before the fusible mass has lost its holding power when the link is traversed by a sufficiently heavy current, said heat absorbing mass being attached to said fusible link between said portion adapted to fuse and said fusible mass.

6. The combination of a receptacle having circuit terminals at least one of which is heat dissipating, of a thermal circuit interrupter in said receptacle comprising a casing having terminals electrically and thermally engaged with said receptacle terminals, a conductor within said casing extended between and electrically connecting said interrupter terminals, a heat absorbent mass thermally connected to said conductor, a readily fusible metal adherent to and mechanically connecting said conductor and that interrupter terminal that is in engagement with the heat dissipating receptacle terminal, said conductor becoming heated by the current traversing it and transmitting heat to said fusible metal, said fusible metal fusing and releasing its attachment with said conductor when said conductor is traversed by a sufficiently heavy current for a sufficiently long time, and spring means responsive to the fusing of said fusible metal to effect separation of the conductor and heat absorbent mass from the associated interrupter terminal.

7. In a thermal circuit interrupter, a casing having terminals, a heating conductor extended between said terminals and having a fusing portion, a readily fusible metal attached to said conductor and one terminal and connecting them, said heating conductor having a large mass of heat absorbing material carried thereby and attached thereto adjacent said readily fusible metal to delay the fusing thereof, and means for interrupting the circuit through the interrupter in response to the fusing of said readily fusible metal.

8. In a thermal circuit interrupter, a casing having terminals, a fusible link having a most readily fusible portion extended between said terminals, a readily fusible metal attached to said fusible link and one terminal and connecting them, said fusible link having a large mass of heat absorbing material thereon between said most readily fusible portion and said readily fusible metal to delay the fusing of said fusible metal, and means responsive to the fusing of said fusible metal to effect separation of said fusible metal and said fusible link.

9. In a thermal circuit interrupter, a casing having terminals, a fusible link extended between said terminals having an intermediate heating and most readily fusible zone, a readily fusible mass connecting said link and a terminal and adapted to be fused by the sufficient heating of said link, a heat absorbing mass connected with and supported by said link between said heating and most readily fusible zone and said readily fusible metal to delay the fusing thereof, and means for interrupting the circuit through said fusible link in response to the fusing of said readily fusible metal.

10. In a thermal circuit interrupter, a casing

having terminals, a fuse link extended between said terminals, a mass of readily fusible metal connecting said fuse link with one terminal, said fuse link having as a unitary part thereof a short-circuit blowing section and a relatively large mass of heat absorbing material additional to the link between said short-circuit blowing section and said readily fusible metal to delay the fusing of the latter, and means for interrupting the circuit through the interrupter in response to the fusing of said readily fusible metal.

11. In a thermal circuit interrupter, a casing having terminals, a fuse link extended between said terminals, a readily fusible metal connecting said fuse link with one terminal, said fuse link having an intermediate portion of reduced cross sectional area, a heat absorbing mass secured to said link between said readily fusible metal and said reduced area portion, and spring means for effecting separation of said link from said readily fusible metal upon the fusing of the latter.

12. In a circuit interrupter, a casing having a terminal and a center contact, a fuse link extended between said terminal and center contact, a readily fusible metal attached to said fuse link and center contact, said fuse link having an intermediate portion of reduced cross-sectional area, a heat absorbent mass fixed to said link between said portion of reduced area and said readily fusible metal, and spring means acting on said link to move it away from said readily fusible metal when the latter fuses.

13. In a thermal circuit interrupter, a casing having terminals, a fuse link extended between said terminals having a heat absorbent mass attached to one end thereof and having an intermediate fusing portion, a readily fusible metal connecting said heat absorbing mass with one terminal, and spring means for separating said heat absorbing mass from said one terminal and readily fusible metal upon the fusing of the latter.

14. In a thermal circuit interrupter, a casing having terminals, a fuse link extended between said terminals having a heat absorbent mass attached to one end thereof and having an intermediate fusing portion, a readily fusible metal connecting said heat absorbing mass with a stationary part of one terminal, and spring means for separating said heat absorbing mass from said one terminal and readily fusible metal upon the fusing of the latter, said one terminal being long and having a contact face at one end thereof and having the readily fusible metal attached to the other face thereof.

15. In a fusible electric circuit interrupter, a casing, having terminals, a fusible conductor extended between said terminals, a mass of heat absorbent material directly thermally connected to said conductor, a mass of readily fusible material electrically and mechanically connecting said mass of heat absorbent material and said conductor to one of said terminals, and spring means arranged to engage said conductor to move the conductor and the mass of heat absorbent material away from its associated terminal for interrupting the circuit through the interrupter in response to the fusing of the readily fusible metal and for separating the fused end portions of the conductor upon fusing of the fusible conductor.
